(57) **CLAIM**

The ornamental design for a snack tray, substantially as shown and described.

DESCRIPTION

FIG. 1 is a perspective view of a snack tray according to the design, shown in an example environment of use in connection with a highchair.

FIG. 2 is a first perspective view of a snack tray according to an embodiment of the design.

FIG. 3 is a second perspective view of the snack tray of FIG. 2.

FIG. 4 is a first end view of the snack tray of FIG. 2.

FIG. 5 is a second end view of the snack tray of FIG. 2.

FIG. 6 is a first side view of the snack tray of FIG. 2.

FIG. 7 is a second side view of the snack tray of FIG. 2.

FIG. 8 is a top view of the snack tray of FIG. 2; and,

FIG. 9 is a bottom view of the snack tray of FIG. 2.

The broken line portions of the drawing figures are included to show portions of the article or environment that are not part of the claimed design.

1 Claim, 4 Drawing Sheets
